UNITED STATES PATENT OFFICE.

HENRY J. GOFF, OF SUSANVILLE, CALIFORNIA, ASSIGNOR TO FRUIT GROWERS SUPPLY COMPANY, OF LOS ANGELES, CALIFORNIA, A CORPORATION OF CALIFORNIA.

METHOD OF AND APPARATUS FOR CONSTRUCTION OF GLUED ENDS FOR PACKING BOXES.

Application filed September 21, 1925. Serial No. 57,636.

This invention relates to the method of and apparatus for the construction of glued ends for packing boxes, such as are described in the copending application of 5 Clement A. Brown and Clyde A. Batchelder, filed January 19, 1925, Serial Number 3,306, fruit box.

In the packing of fruit, vegetables, and the like, packing boxes are employed which 10 are constructed of wood. The construction of these packing boxes must be such that the same are of light weight but are of sturdy construction to enable them to withstand the handling received during the shipping thereof. The end members employed 15 in the construction of these boxes have been and are at present in many instances formed of single portions of wood which are expensive and difficult to obtain in the sizes required for the construction of the boxes 20 and as the supply of wood becomes more or less limited in any particular locality it becomes more difficult to obtain wood of sufficient width to prepare or form the end 25 sections of single portions thereof, and also as the supply of wood in any particular locality becomes diminished, the quality of the wood likewise decreases so that it is extremely difficult to obtain single pieces of 30 wood of great enough width to prepare these box ends which are not of such inferior quality that the same, on being employed for the construction of boxes, will split when 35 nails, staples, or the like, are driven into the same during the construction of the boxes.

A box end constructed in accordance with the disclosure in the application for fruit box, Ser. No. 3,306, above referred to, is extremely well adapted to take the place of a single portion of wood box ends heretofore employed, and is of cheaper construction and greater reliability and durability in that the same eliminates the liability of splitting.

45 It is an object of this invention to provide a method of construction of the box ends constructed of a plurality of relatively narrow strips of wood secured together by means of cleats glued to the ends of the 50 strips of wood.

Another object of this invention is to provide a method for the construction of box ends of a plurality of strips of wood glued together at their ends in which method the

strips of wood employed are formed or cut 55 to their proper width and length and secured to provide box ends for the construction of packing boxes.

Another object of this invention is to provide a method of gluing the retaining cleats 60 or strips to the ends of the strips of material after the same have been properly cut and squared.

Another object of this invention is to provide an apparatus for carrying out the process 65 embodying the above set forth objects.

Other objects and advantages of this invention will be apparent from the following detailed description of a preferred embodiment thereof as illustrated in the accompanying drawings.

In the drawings:

Fig. 1 is a top plan view of apparatus for the construction of glued ends of packing boxes embodying this invention. 75

Fig. 2 is an end elevation thereof, taken substantially on the line 2—2, of Fig. 1.

Fig. 3 is an end elevation thereof taken substantially on the line 3—3 of Fig. 1.

Fig. 4 is a perspective plan view of a gluing frame comprising this invention. 80

Fig. 5 is a perspective plan view of a completed glued box end constructed in accordance with the process embodying this invention. 85

In the preferred embodiment of this invention illustrated in the accompanying drawings, the apparatus includes means for cutting and squaring strips of material 1 which means comprise a guideway 2 upon 90 which a plurality of strips of material 1 are placed, which strips of material are of greater length, and their combined width is greater than the width, required for the box end. A guide rail 3 is secured to the 95 guideway 2 and guides the strips of material at one edge thereof. A pusher block 4 is mounted in the guideway to engage the rearward edge of the strips of material 1. A slide block 5 is mounted in a slot 6 formed 100 in the guideway 2 and supports the strips of material 1 during their travel along the guideway 2.

The operator grasps the handle 7 of the pusher block 4 and causes the strips of material 1 to move along the guideway 2 past a rotating saw 8 which saw acts to cut the strips of the material to the proper width. 105

The rotating saw 8 is of any desired or preferred construction and manner of operation, and is herein illustrated as secured to a shaft 9 at a collar 10 which shaft 9 is 5 also rigidly secured to a belt pulley 11 which belt pulley 11 may be driven through auxiliary pulleys 12 through a belt connection from a drive shaft 13. The pusher block 4 is cut away, as illustrated at 14, to 10 permit the saw 8 to cut through the outer strip of material 1 without cutting the forward engaging edge of the pusher block 4. The strips of material 1 are then advanced to the position illustrated at B over a second runway 15 where the same are engaged 15 by means of a pusher block 16 and conveyed along the slide 17 mounted in the slot 18 past a pair of saws 19 where the strips of material 1 are cut to the proper length 20 and squared at their ends. The saws 19 are secured to shafts 20 at collars 21 to which shafts 20 pulleys 22 are secured, which pulleys 22 are driven by belts from the drive shaft 13.

25 The strips of material 1, having been properly cut and squared, are advanced along the runway 15 to the position C. The strips of material 1 are now ready to be glued to and hold the reinforcing and holding strips or cleats 23.

For gluing the strips of materials 1 to the reinforcing strips 23, I prefer to employ the following means:

A plurality of such cleats 23 are mounted 35 in a magazine 24 adjacent a glue pot 25, four of such cleats 23 being mounted side by side, the cleats 23 having been previously formed to the correct length and width for the formation of the box ends and for 40 gluing to the two ends of the strips of material 1, the pusher block 26 is mounted on a platform 27 in position to eject the cleats 23 from the magazine 24. The pusher block 26 is pivotally connected at a pin 28 to a link 29 which link 29 is pivotally connected at a pin 30 to a rocker arm 31, which is pivotally connected at its opposite end at a pin 32 to the stationary member 33. The rocker arm 31 is pivotally connected intermediate its ends at a pin 34 to a rod 35, which rod 35 is pivotally connected at a pin 36 to the operating lever 37, which is angled at its lower end to form a foot pedal 38. The operating lever 37 is pivotally connected 50 at a pin 39 to a second stationary support 40. In order to hold the pusher block 26 in the ejecting position, a weight 41 is connected to a cable 42 which is trained over a pulley 43 and is secured to the outer end 55 of the link 29. The pulley 43 is rotatably supported in a bracket 44 secured to the framework of the apparatus.

An operator stepping on the foot pedal 38 causes four cleats 23 to be moved under the discharge spout 45 of the glue pot 25

and to receive glue on their upper surfaces. A portion of felt or other material 46 is mounted in position to remove the surplus glue from the surfaces of the cleats 23. In order to securely hold the strips of material 1 in engagement with the cleats 23 during the gluing of the cleats 23 to the ends of the strips 1, a gluing frame 47 is provided within which a plurality of box ends may be formed. The gluing frame 47 is herein 75 illustrated as being formed to accommodate two such box ends. However, it is to be understood that any suitable or desirable number of box ends may be glued in such a gluing frame 47.

The operator having ejected four cleats 23 from the magazine 24 past the glue pot 25, takes these cleats 23 and positions one of them as at 48. The strips 1 having been properly squared and cut are then moved 85 from the position C to the position D where their ends are in engagement with the glued surface of the cleat 23. A second cleat 23, having glue on its engaging surface, is then positioned at 49. A third cleat is then taken 90 and positioned with its glued surface away from the cleat 23 into the position 49. A second group of strips 1 are then moved into position to engage the last mentioned cleat 23. The last cleat 23 of the group 95 is then taken by the operator and applied to the outer surface of the last group of strips 1 in the position illustrated at 50 in Fig. 4.

The gluing frame 47 is then moved to 100 position in the clamping apparatus 51 which clamping apparatus 51 is preferably of the following construction and operation:

The gluing frame 47 has slots 52 at its outer ends into which a clamping wedge 53 is adapted to be forced with its straight edge 54 in engagement with the cleat 23 which is in the position 50. The opposite edge 55 of the wedge 53 is tapered for a purpose that will hereinafter appear. The clamping apparatus 51 comprises a platform 56 onto which the clamping frame 47 is positioned. A hold-down plate 57 is mounted in position so that the same may be engaged with the upper surface of the strips 1 to hold the same from buckling during the clamping operation. The hold-down plate 57 is pivotally secured at the pin 58 to a link 59 which link 59 is pivotally supported at its opposite end at a pin 60 to a rocker arm 61, which rocker arm is pivotally supported at a pin intermediate its ends at a pin 62 in a bracket 63 secured to the frame of the apparatus. The rocker arm 61 is pivoted at a pin 64 to a link 65 which link 65 is pivotally secured at its opposite end at a pin 66 to an operating pedal 67, which operating pedal is pivotally supported at a pin 68 mounted in a standard 69.

A weight 70 is secured to the rearward

end of the operating pedal 67 so as to normally maintain the hold-down plate from engagement with the strip of material 1 and cleats 23. The wedge 53 is inserted in proper position into the slots 52 formed in the ends of the gluing frame 47. When the hold-down plate is properly engaged with the upper surfaces of the strips 1 and cleats 23, the operator opens the air line 71 at the valve 72 to supply air pressure to the cylinder 73 within which cylinder 73 a piston (not shown) is mounted to reciprocate and which piston is connected by means of a piston rod 74 at a pin 75 to an arm 76 which is pivotally supported at a pin 76^a mounted in a standard 77. The arm 76 is pivotally supported at its opposite end 78 to a connecting link 79 which is pivotally connected at a pin 80 to a wedge-engaging member 81, which wedge-engaging member 81 is pivotally supported at its lower end at a pin 82 to a standard 83. The wedge-engaging member 81 is guided in a guideway 84 so as to be in position to engage at its forward edge 85 the outer end of the wedge 53. The wedge-engaging member 81 engages the wedge 53 and causes the same to be forced through the slots 52 so as to clamp the strips 1 of the material in engagement with the respective cleats 23. After the wedge 53 has been properly forced into position the operator releases the pedal 67 and permits the engaging plate 57 to raise from engagement with the members 1 and 23 and gluing frame 47 is lifted from the platform 56 and set aside to permit the glue to harden to properly unite the member 1 and 23.

From the foregoing, it will be apparent that my method or process consists in the steps of first, forming the strips of material to their proper width; second, forming the strips of material to their proper length; third, positioning the strips of material in engagement with reinforcing cleats in a gluing frame; and 4, wedging or gluing the strips of material and the reinforcing cleats in engagement to permit the glue to harden to unite the same.

Having fully described a preferred embodiment of this invention, it is to be understood that it is not intended that the same should be limited to the exact details herein set forth which may, obviously, be varied in detail without departing from the spirit of the invention as set forth in the appended claims.

I claim:

1. A method of forming glued packing box ends which comprises cutting a plurality of strips of material to a predetermined combined width, cutting the strips of material to a predetermined length while squaring the same, positioning glued holding cleats at the ends of said strips with their glued faces adjacent the ends of the

strips and clamping the strips and cleats together.

2. A method of forming glued packing box ends which comprises cutting a plurality of strips of material to a predetermined combined width, cutting the strips of material to a predetermined length while squaring the same at their ends, applying glue to the engaging faces of a plurality of cleats, positioning the cleats in engagement with the squared ends of the strips with the glued faces in engagement with the ends of the strips and clamping the strips and cleats in engagement. 70

3. The method for forming glued box ends for packing boxes which comprises cutting a plurality of strips of material to a predetermined and combined width, cutting strips of material to a predetermined length while squaring the same and applying glue to the engaging faces of a plurality of cleats, positioning the cleats in engagement with the squared ends of the strips in a gluing frame so as to clamp a plurality of box ends in a single gluing frame. 80

4. The method of forming glued packing box ends which comprises cutting a plurality of strips of material to a predetermined width, cutting the strips of material to a predetermined length while squaring the same at their ends, applying glue to the engaging faces of a plurality of cleats, positioning the cleats in engagement with the squared ends of the strips with the glued faces in engagement with the ends of the strips, holding the strips and cleats flat on a table in a clamping apparatus and wedging the cleats and strips in engagement horizontally. 90

5. A method of forming packing box ends which comprises cutting a set of strips of wood to a predetermined combined width, cutting the said set of strips of material to a predetermined length, cutting a second set of strips of material to the same predetermined combined width, cutting the said second set of strips to the same determined length, applying glue to the engaging faces of a plurality of cleats, positioning a cleat in engagement with the opposite ends of each set of strips of material in a gluing frame, and with the adjacent cleats in engagement, holding the sets of strips of material and cleats flat on a table and wedging the said cleats and strips together in said frame. 105

6. In an apparatus for forming glued packing box ends from a plurality of relatively narrow strips of material, a guideway having a guiderail at one side thereof, means for moving the strips of material along the guideway, means for cutting one of the said strips longitudinally while the same are being pushed along the guideway, a second guideway formed at right angles 110

to the first said guideway, means for conveying the said strips of material along the second guideway, means mounted at the edges of the guideway for guiding the strips of material at their ends to predetermined length and to square the same, means for applying glue to the engaging faces of a plurality of cleats, a gluing frame, and means for clamping the strips of material in engagement with the cleats so that the glue-engaging faces of the cleats are in engagement with the ends of said strips.

7. In combination with an apparatus for forming glued ends for packing boxes, a gluing frame comprising a substantially rectangular frame adapted to receive a plurality of box-ends composed of a plurality of strips of wood, to the opposite ends of which cleats are secured, the adjacent cleats of which box-ends are positioned in engagement, a wedge adapted to be slidably engaged in the rectangular frame to wedge the said box-ends longitudinally in the frame, means for holding the box-ends flat on a table, and means for operating the said end-wedge means when the said box-ends are held flat on the table.

8. A method of forming glued box-ends which comprises placing a plurality of strips of material on a supporting runway with their longest adjacent edges in engagement, guiding the strips while the same move along the said supporting runway, cutting one of the said strips to form all of the said strips to a combined predetermined width while moving and guiding the same along the runway, moving the said strips along the runway in a direction transverse to the said adjacent edges of the strips, cutting the strips at their opposite ends to a predetermined length while so moving the same along the supporting runway, positioning the said strips in a clamping frame on the said supporting runway in engagement with

cleats, to the engaging faces of which glue has been applied, holding the said strips in engagement with the cleats while clamping the same together, holding the said cleats and strips flat against the said supporting runway while clamping the same in the said clamping frame on the said support and removing the said clamping frame, strips and cleats together from the said support.

9. In an apparatus of the class described, the combination of a supporting runway having a transverse section and a pair of parallel sections, means for guiding and moving a plurality of strips of wood along one of the parallel sections, a rotary cutting element mounted at one edge of the said parallel section for cutting the said strips to a predetermined combined width, means for moving the said strips along the said transverse section, oppositely disposed rotary cutting means mounted on the opposite sides of the said transverse section of the supporting runway for cutting the said strips to a predetermined length, a gluing frame adapted to be supported on the second parallel section of the said supporting runway and adapted to receive a plurality of the said strips which have been cut to the said predetermined length and width, means for applying glue to the engaging faces of a plurality of cleats which are adapted to be positioned within the said gluing frame with their glued faces in engagement with the ends of the said strips and so that the adjacent cleats which are engaged with the edges of the said strips are in engagement, means for holding the said strips and cleats flat against the table, and means for wedging the said cleats and strips together in the said gluing frame while the same are held flat against the said supporting runway.

Signed at Susanville, California, this 4th day of September, 1925.

HENRY J. GOFF.
